THE NORRIS PETERS CO., WASHINGTON, D. C.

UNITED STATES PATENT OFFICE.

RICHARD KERSEY, OF LEXINGTON, KENTUCKY, ASSIGNOR OF ONE-HALF
TO EDGAR ALLAN CARR, OF LAWRENCEBURG, KENTUCKY.

WINDOW-SCREEN.

No. 838,864.

Specification of Letters Patent.

Patented Dec. 18, 1906.

Application filed October 6, 1905. Serial No. 281,625.

To all whom it may concern:

Be it known that I, RICHARD KERSEY, a citizen of the United States, residing at Lexington, in the county of Fayette and State of Kentucky, have invented a new and useful 5 Window-Screen, of which the following is a specification.

The invention relates to improvements in window-screens.

10 The object of the present invention is to improve the construction of window-screens, and to provide a simple and comparatively inexpensive one adapted to be readily applied with slight change to the top and bottom of a 15 window and connected with the sashes thereof for screening the top and bottom of a window when the sashes are open.

A further object of the invention is to provide a window-screen of this character adapted 20 to effectually exclude flies or other insects and capable of automatically rewinding itself when a sash is closed and of relieving the sash of the tension of the spring for rewinding the screen, so that the spring will not close an 25 evenly-balanced sash.

Another object of the invention is to provide means for preventing flexible screen material, such as mosquito-netting and the like, from being worn through its attachment 30 to a sash.

With these and other objects in view the invention consists in the construction and novel combination and arrangement of parts hereinafter fully described, illustrated in the 35 accompanying drawings, and pointed out in the claims hereto appended, it being understood that various changes in the form, proportion, size, and minor details of construction within the scope of the claims may be 40 resorted to without departing from the spirit or sacrificing any of the advantages of the invention.

In the drawings, Figure 1 is an elevation of a window provided with upper and lower 45 screens constructed in accordance with this invention. Fig. 2 is a vertical sectional view of the same, taken substantially on the line 2 2 of Fig. 1. Fig. 3 is a perspective view of the lower screen, showing the same detached. Fig. 4 is an enlarged detail horizontal sectional view of one side of the screen. Fig. 5 is a detail perspective view of a portion of the screen, showing one of the metallic loops. Fig. 6 is an enlarged detail sectional 50

view taken substantially on the line 6 6 of 55 Fig. 7 and illustrating the manner of mounting one end of the spring-actuated roller. Fig. 7 is a detail sectional view taken substantially on the line 7 7 of Fig. 6. Fig. 8 is a detail sectional view illustrating the manner of mounting the other end of the roller. 6c

Like numerals of reference designate corresponding parts in all the figures of the drawings.

1 designates the frame of the window- 65 screen, which, as illustrated in Figs. 1 and 2 of the drawings, is adapted to be applied at both the top and bottom of a window, and when applied at the top it is located on the exterior of the window and on the interior 70 when arranged at the bottom of the window. The frame 1 is substantially U-shaped and is composed of vertical sides 2 and a connecting transverse portion 3, which is in the form of a casing and which houses a spring-actuated roller 4. The sides 2 are substantially 75 L-shaped in horizontal or cross section to fit snugly a window frame or casing 5. The spring-actuated roller on which the flexible screen material 6 is wound is similar in construction to the spring-actuated roller of an ordinary window-shade, and its round journal 7 is arranged in a suitable bearing 8 at one end of the casing 3, which is provided at the other end with a rectangular aperture 9 for 80 the reception of the journal 10, which is connected with the spring of the roller. The bearings, which may be constructed in any suitable manner, preferably consist of plates of sheet metal or other suitable material supported by suitable blocks or pieces 11 and 12. 85

The sides 2 of the screen-frame are provided with longitudinal openings 13, extending from a slot or opening 14 of the transverse casing and receiving flat longitudinal guide-bars 15, on which slide loops 16 of the flexible screen 6. The flexible screen 6 may be made of mosquito-netting or any other suitable screen material, and the loops 16, which are approximately U-shaped, extend horizontally from the ends of a slide 17, consisting of a cross bar or member extending entirely across the frame and provided with means for detachably connecting it to a window-sash. The slide 17, which forms a cross-bar, preferably consists of intermediate and side pieces, the loops 16 being secured to the intermediate piece, as clearly shown in Fig. 90 100 105

4. The outer transverse edge of the screen material is also secured between two of the pieces of the slide 17, and the side edges of the flexible screen are passed around the 5 guide-bars and stitched or otherwise secured to form hems or casings 18, whereby they are slidably connected with the said guide-bars. The unrolled portion of the screen is connected at each side throughout its entire 10 length with the bars by the hems or casings. These guide-bars, which terminate short of the bottom of the casing, have enlarged upper ends, which are secured between the bars or members of the sides 2. These bars or 15 members, which are spaced apart to provide the vertical openings 13, are preferably connected at the top by substantially L-shaped cap-pieces 3^a. The loops 16 are each composed of two plates or pieces which receive 20 the flexible screen between them, as clearly shown in Fig. 5 of the drawings. The slide 17, which is provided at the outer faces of the sides 2 of the frame 1 with extensions 19, is detachably secured to the window-sash by 25 means of catches 20. The extensions 19 overlap the sides 2 of the frame and are adapted to slide thereon. The catches 20, which are preferably in the form of hooks, engage the bottom bar 21 of the lower sash 22 30 or the upper bar 23 of the upper sash 24 and are provided with eyes 24^a, which are linked into eyes 25 of the slide 17. By this construction the flexible screen material is prevented from being worn or otherwise injured through its attachment to the sashes of 35 the window.

When either of the sashes of the window is opened, the flexible screen connected with such sash is unwound from its roller, and 40 when the sash is closed the flexible screen is automatically rewound on the roller by the spring of the latter. In order to relieve the sashes of the tension of the spring and prevent the latter from closing, an evenly-balanced sash, a ratchet-wheel 26, and a dog 27 are provided. The ratchet-wheel is mounted 45 on the roller 4 at the round journal 7, and the dog, which is in the form of a lever, is pivoted at its inner end 28, and its outer end extends 50 through a slot 29 of the outer wall of the casing 3. The casing at the bottom of the window is provided at the outer side of the slot 29 with a shoulder 30, adapted to support the pivoted dog 27 out of engagement 55 with the ratchet to permit the spring-actuated roller to automatically wind up the flexible screen as the sash is closed. The dog of the upper window-screen is adapted to rest upon the ratchet-wheel, and it may be 60 omitted, if desired, or any suitable means may be employed for lifting the upper dog out of engagement with the upper ratchet-wheel. When the catches are disengaged from the sashes, the screens will remain 65 wound on the spring-actuated roller, and the

latter will automatically rewind the flexible screens should the same be detached from the sashes and the pawls or dogs disengaged from the ratchet-wheels.

By slidably connecting the side edges of the screen material with the vertical guides of the sides of the frame 1 insects are effectively prevented from passing around the side edges of the screen, and a guard consisting of a strip 31 is preferably mounted on the upper sash at the bottom thereof to close the space between the sashes when the same are partly open, as illustrated in Fig. 2 of the drawings, to prevent any insects from crawling upward between the sashes. This strip 80 is preferably constructed of rubber or other yieldable material; but it may be constructed of wood, metal, or other inelastic material. The screen-frame and roller may be made of either wood or metal. 85

Having thus fully described my invention, what I claim as new, and desire to secure by Letters Patent, is—

1. A window-screen, comprising a frame provided with vertical sides and having a connecting portion, a flexible screen provided with a roller mounted within the connecting portion, a slide movable on the sides of the frame and attached to the flexible screen and arranged to fit against one edge of the end bar of a sash, and a hook-shaped catch hinged to the slide and arranged to engage the end bar of the sash at the edge opposite that against which the slide fits. 95

2. A window-screen, comprising a frame provided with sides having interiorly-arranged guide-bars, a flexible screen provided with a roller mounted in the frame, and a cross-bar attached to the flexible screen and provided with loops embracing the flexible screen and extending therefrom and also secured to the cross-bar, said loops being slideable on the said guide-bars. 100

3. A window-screen, comprising a frame composed of sides having longitudinal openings, and a connecting-casing provided with a slot connected with the said openings, guide-bars mounted within the openings of the sides of the frame and having free ends located adjacent to the said slot, a flexible screen slideable on the guide-bars and having its side edges embracing the same, means for connecting the screen with a sash, and a roller mounted within the casing and connected with the flexible screen. 110

4. A window-screen, comprising a frame provided at opposite sides with openings, guide-bars located within the openings, a flexible screen slideable on the guide-bars and having its side edges embracing the same, loops fixed to the flexible screen at the side edges thereof and slideable on the guide-bars, and means for connecting the screen with the sash. 115

5. A window-screen, comprising a frame 120

having openings at opposite sides, guide-bars arranged in the openings, a slide provided with substantially **U**-shaped loops slideable on the guide-bars and composed of plates or members, and a flexible screen attached to

5 the slide and extending between and engaged by the said plates or members, said flexible screen being provided with a roller mounted in the casing.

10 6. A window-screen comprising a frame provided with vertical sides and having a connecting portion, a flexible screen provided with a spring-actuated roller mounted within the connecting portion of the casing, a 15 ratchet-wheel connected with one end of the roller, a pivot mounted on the connecting portion of the casing at one side of the roller, and a pawl or dog extending across the connecting portion of the frame and connected 20 at one end to the same by the said pivot, and provided at an intermediate point with means

for engaging the ratchet-wheel, the other end of the pawl or dog being extended through the opposite side of the connecting portion of the frame to enable it to be exteriorly operated. 25

7. In a window-screen, the combination of a frame composed of vertical sides substantially **L**-shaped in cross-section, and a connecting portion arranged at one end of the 30 frame, flat guide-bars fitted in the sides of the frame, and a screen provided at opposite sides with approximately **U**-shaped loops slideable on the flat guide-bars.

In testimony that I claim the foregoing as 35 my own I have hereto affixed my signature in the presence of two witnesses.

RICHARD KERSEY.
